United States Patent Office

Des. 181,574
Patented Dec. 3, 1957

181,574

SPOON OR SIMILAR ARTICLE

Nord Bowlen, Greenfield, Mass., assignor to Rogers,
Lunt & Bowlen Company, Greenfield, Mass., a corporation of Massachusetts

Application March 29, 1956, Serial No. 40,832

Term of patent 14 years

(Cl. D54—12)

Fig. 1.

Fig. 2.

Fig. 5.

Fig. 1 is a front view of a spoon embodying my design;

Fig. 2 is a side view of the spoon;

Fig. 3 is a cross-section along line 3—3 of Fig. 1;

Fig. 4 is a cross-section along line 4—4 of Fig. 1; and

Fig. 5 is a rear view of the spoon.

The handle of the spoon is lined to indicate the color black.

I claim:

The ornamental design for a spoon or similar article, substantially as shown and described.
